[57] ABSTRACT

An open cycle heat engine supplies steam from a steam generator to an ejector in which the moving steam draws in atmospheric air to mix with the steam to make a flowing air-steam mixture. A first nozzle follows the ejector and effects adiabatic expansion of the air steam mixture. A thermal engine, e.g., a turbo-generator, has an input connected to the first nozzle and an outlet, and converts the kinetic energy in the mixture into a useful form, such as electricity. A second nozzle connected to the outlet of said thermal engine effects adiabatic expansion of the mixture leaving the thermal engine, and exhausts it to the atmosphere. The open cycle heat engine exhaust is at a low density, and is carried aloft when it is discharged into the atmosphere. This open cycle can have an energy conversion efficiency of 90%.

5 Claims, 1 Drawing Sheet

FIG. 1

HEAT ENGINE

BACKGROUND OF THE INVENTION

This invention relates to heat engines, and is more particularly related to an open-cycle heat engine in which steam is employed as a source of heat. The invention is more specifically concerned with a thermodynamic process employing air and water vapor as the working fluid, which expands and cools to produce work and exhausts from the system at a temperature below the earth's average ambient temperature.

All matter contains energy in the form of heat energy or enthalpy. This energy flows in one direction only, that is, from material at high temperature to material at low temperature. The flow of energy is heat, and can be compared with fluids, such as water, which flows to produce work. In the case of water, potential energy in the form of elevated water is converted to kinetic energy in the form of flowing water. Some of this kinetic energy is converted to useful energy, i.e., work, by an engine such as a water turbine. The rest of the kinetic energy is discarded as waste. In the case of a hot material, which stores energy, i.e., enthalpy, and this energy is converted to kinetic energy by permitting the material, i.e., a gas, to expand and flow. Some of this kinetic energy can be converted to useful work, e.g., in a gas turbine. The remainder of the kinetic energy is discarded as waste heat, and ultimately winds up in the atmosphere.

Every heat engine requires a working medium, which can typically be steam or another working gas. In modern engines, this working medium is usually gaseous or vaporous in form, with the preferred choice being steam. Early steam engines had an energy conversion efficiency of less than 5%, and discarded 95% of their initial energy as waste heat to the atmosphere. By the development of improved engines, including the development of the Rankine Cycle, and with the addition of condensers and water pumps, conversion efficiency was increased to 20% and above. More recently, turbine design improvements, such as feed water heating, higher operating temperatures, superheating, reheat cycles, etc., have further increased conversion efficiency to exceed 35%. However, improvements much above this efficiency level have been elusive in the heat engine arts.

OBJECTS AND SUMMARY OF THE INVENTION

Accordingly, it is an object of this invention to provide a heat engine with an improved cycle, achieving greater conversion efficiencies than previously.

It is another object to provide an open cycle heat engine using a thermodynamic process in which air and water vapor are used as the working fluid.

It is another object to provide an open cycle heat engine in which the working fluid expands and cools in an exhaust nozzle to a temperature below the earth's average ambient temperature.

It is a more specific object to provide an open cycle heat engine wherein a jet of low density high velocity exhaust working fluid penetrates the ambient atmosphere to be lifted to altitude by its buoyancy.

In accordance with an aspect of the present invention, an open cycle heat engine comprises a supply of a hot first working fluid, e.g., steam, which is supplied to an ejector. The injector draws in atmospheric air to combine with the steam, so that the air and steam serve as the final working fluid. Then this mixture passes into a heat engine through a

first expansion nozzle. The flowing mixture is expanded adiabatically with decreasing temperature in the first nozzle to achieve a high velocity as the enthalpy is converted to kinetic energy. This flow is directed into the turbo-generator 5 where most of the kinetic energy of the mixture is converted first to rotational energy and then to electricity. The flow is then directed to a second nozzle for a constant temperature adiabatic expansion of the leaving gases, condensing the remaining vapor, as latent heat is converted to kinetic energy. The high velocity flow is exhausted to the ambient, where it penetrates the atmosphere and is lifted to altitude for disposal.

The above and many other objects, features, and advantages of this invention will become apparent to persons skilled in the art from the ensuing description of a preferred embodiment, which is to be read in conjunction with the accompanying Drawing.

BRIEF DESCRIPTION OF THE DRAWING

The sole Drawing FIGURE schematically illustrates an embodiment of the open cycle heat engine of this invention.

DETAILED DESCRIPTION OF THE PREFERRED EMBODIMENT

With reference to the Drawing, the sole FIGURE illustrates the basic principles of the open cycle heat engine 10 of this invention. A steam generator 12 (generically rendered here) takes the energy from a heat source 14 and produces steam, which it supplies to an ejector 16. The ejector can be of a well known construction, and has been well described in the relevant literature. An ejector can be defined as a device in which the kinetic energy of one fluid, e.g., steam, is used to pump another fluid, i.e., air, from a region of lower pressure to a region of higher pressure.

The steam-air mixture, at high velocity, passes to a first nozzle 18, where the flowing mixture is expanded adiabatically (i.e., at constant entropy) with decreasing temperature to achieve a high velocity as its enthalpy is converted to kinetic energy. The flow is directed to a turbo-generator 20, where the kinetic energy of the mixture is used to rotate the turbine shaft 22, and this rotational energy can be used to generate electricity. Then, the fluid mixture leaving the turbo-generator 20 is directed to a second nozzle 24, for a constant-temperature adiabatic expansion. This condenses the remaining vapor as its latent heat is converted to kinetic energy. The high velocity flow penetrates the atmosphere and lifts to altitude for disposal.

A study of the atmospheric phenomena applying thermodynamic methods observes the following conventions and constraints: (1) standard thermodynamic formulae; (2) standard steam tables (e.g., Keenan & Keyes Steam Tables); (3) values of thermodynamic constants:

55	Constants	Air	Steam
heat capacity (const. pressure) C_p	0.241	0.47	
heat capacity (const. volume) C_v	0.173	0.36	
$R = J^*(C_p - C_v)$	52.904		
heat constant k	1.393		

- 60 (4) Reference levels (initial): $T_0=32^\circ F$. ($491.6^\circ R$); $P_0=15$ psi (pounds per square inch);
 $V_0=12.040\ 558\ 52$; $E_0=0$; $H_0=0$; $S_0=0$;
 (5) the relation of air and water vapor properties, temperature T , volume V , pressure P , enthalpy H , energy E , and entropy S , where the subscripts V, A, and M represent vapor, air, and mixture, respectively:

$$T_V = T_A = T_M$$

$$V_V = V_A = V_M$$

$$P_V + P_A = P_M$$

$$H_V + H_A = H_M$$

$$E_V + E_A = E_M$$

$$S_V + S_A = S_M$$

(6) Condensed water vapor remains in the mixture.

The conditions for the steam and steam/air mixture at various stages though the system can be seen from the following tables. As mentioned before, the values of the steam parameters are published values, taken from the Keenan and Keyes steam tables.

Given that atmospheric air is at 80° F., 14.696 psi, 60° F. DP

For these calculations, we assume conditions of atmospheric air at 80° F., 14.696 psi pressure, with a dew point of 60° F., and that this is combined in the ejector with 0.04 pounds of saturated steam at 220° F. containing 46.136 btu of energy, to produce an air-vapor mixture with the following properties (see Table 220—Input):

$$W_m = 0.050 955 638$$

$$S_m = 0.1 17 941 625$$

$$H_m = 69.726 717 41$$

The flowing mixture leaves the ejector 16 at 103° F. and 16 psi pressure with a kinetic energy of 4.7 btu (see Table 103). In the first nozzle 18 an adiabatic expansion reduces the temperature from 103° F. to 32° F., converting additional enthalpy for a total of 55.3 btu as kinetic energy. (See Table 32 Turbo-generator entry). The turbo-generator 20 converts 75% of the kinetic energy (41.5 btu) to useful output energy (i.e., electricity) with 13.8 btu remaining in the flow as kinetic energy. (See Table 32—turbo-generator exit—2nd nozzle entry). In the second nozzle 24, an adiabatic expansion at a constant temperature of 32° F. completes condensation of the remaining vapor converting latent heat of

vaporization to kinetic energy for a total kinetic energy at the second nozzle exit of 28.2 btu. More important, however, is the significant increase in the specific volume of the flow. (See Table 32—2nd nozzle exit).

5 The mixture leaving the second nozzle 24 has a kinetic energy of 28.3 btu, which calculates to a velocity of

$$Vel. = 223.7 \times (KE/W)^{1/2} = 1160.8 \text{ ft/sec}$$

$$10 \text{ Area of exit} = \text{specific volume} \times \text{velocity} = 68.2/1161 = 0.058 742 413 \text{ ft}^2$$

To approximate the distance of penetration of the exhaust jet into the atmosphere (assuming the jet exhaust does not break-up or intermingle with atmospheric air) using the impulse-momentum equation: $FT = mV$, or momentum equals force times time of impulse.

$$20 \text{ Atmospheric resisting force} = 144 \times P \times \text{exhaust area} \\ = 144 \times 14.696 \times 0.058742 = 124.3 \text{ pounds, and}$$

$$\text{Impulse time } T = m \times \text{Vel.} + F = (1.050955638/32.2) \times 1161/124.3 = 0.305 \text{ sec.}$$

$$\text{Distance of penetration} = 1161 + 2 \times 0.304 = 177 \text{ feet.}$$

$$25 \text{ The density of the ambient atmosphere is taken as } 1.010955638 + 13.72902792 \\ = 0.073636630 \text{ lbs/ft}^3$$

$$\text{The density at the second nozzle 24 exhaust is } 1.050955638 + 68.21854776$$

30 During the penetration of the ambient atmosphere, this difference in densities results in buoyancy to lift the system exhaust to altitude well above the exhaust nozzle 24, eliminating any resistance to the exhaust.

35 Thermal efficiency of this system, that is, work output divided by heat input, is 41.5+46.7, or an efficiency of 90%.

While the invention has been described in detail with respect to one preferred embodiment, it should be recognized that there are many alternative embodiments that would become apparent to persons of skill in the art. Many modifications and variations are possible which would not depart from the scope and spirit of this invention, as defined 40 in the appended claims.

I claim:

1. Open cycle heat engine which comprises a) a source of steam at an elevated temperature, b) an ejector to which said steam is supplied from said source, which draws in atmospheric air to mix with said steam to make a flowing air-steam mixture, c) a first nozzle following said ejector for adiabatic expansion of the air steam mixture, d) a turbine, having an input connected to said first nozzle and an outlet, for converting kinetic energy in said mixture into useful work, and e) a second nozzle connected to the outlet of said turbine for adiabatic expansion of the mixture leaving said open cycle heat engine, and for exhausting same to the atmosphere.

2. Open cycle steam engine according to claim 1 wherein said turbine includes a turbo-generator.

3. Open cycle steam engine according to claim 1 wherein ejector includes a device in which kinetic energy of the steam entering the device pumps in air from the atmosphere to flow with the steam to the first nozzle.

4. Open cycle steam engine according to claim 1 wherein said second nozzle expands said leaving mixture to a jet of low density and high velocity to penetrate the ambient atmosphere at a temperature below the average ambient air temperature.

5. Open cycle steam engine according to claim 1 wherein said source of steam provides water vapor as said steam.
